UNITED STATES PATENT OFFICE

139,160

DESIGN FOR A CORK EXTRACTOR

Cyril Hiscock, St. John's, Newfoundland

Application June 3, 1944, Serial No. 113,850

Term of patent 3½ years

(Cl. D44—29)

To all whom it may concern:

Be it known that I, Cyril Hiscock, a citizen of Newfoundland, residing at St. John's, Newfoundland, have invented a new, original, and ornamental Design for a Cork Extractor, of which the following is a specification, reference being had to the accompanying drawing, forming part thereof.

Figure 1 is a side elevational view of a cork extractor showing my new design, and

Figure 2 is an end elevational view thereof.

I claim:

The ornamental design for a cork extractor, as shown.

CYRIL HISCOCK.
